(57) **CLAIM**

We claim the ornamental design for a transducer, as shown and described.

DESCRIPTION

FIG. 1 is a top, front, right perspective view of a transducer showing my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines are included for the purpose of illustrating portions of the transducer that form no part of the claimed design.
